LADDER ATTACHMENT

Nicholas Bengert, New Orleans, La.

Application May 26, 1943, Serial No. 488,583

1 Claim. (Cl. 228—63)

This invention relates to new and useful improvements in ladder structures, and more particularly to means whereby the lower ends of the ladder runners can be adjusted to permit safe use of the ladder on uneven or inclined surfaces.

An important object of the present invention is to provide an attachment of the character stated which can be conveniently attached to conventional ladders.

Another important object of the invention is to provide a ladder attachment of the character described which can be not only readily attached to a conventional ladder, but conveniently adjusted to meet demands.

Other objects and advantages of the invention will become apparent to the reader of the following description.

In the drawings:

Figure 1 is a side elevational view of a ladder showing the adjusting means adjusted to permit use of the ladder on a stairway.

Figure 2 is a side elevational view of the lower portion of a ladder showing the attachment installed.

Figure 3 is a fragmentary detailed sectional view showing the attachment applied to a ladder.

Figure 4 is a section on line 4—4 of Figure 1.

Figure 5 is a top plan view of one of the frames of the attachment.

Figure 6 is a side elevational view of one of the frames of the attachment.

Figure 7 is a side elevational view looking at the opposite side from that shown in Figure 6.

Figure 8 is an end elevational view of the frame shown in Figure 6.

Figure 9 is a fragmentary side elevational view with a portion broken away showing the pressure foot and screw.

Referring to the drawings wherein like numerals designate like parts, it can be seen that numeral 5 generally refers to a ladder of conventional construction, the same having a pair of runners 6, 6 connected by rungs 7.

An adjustable leg structure generally referred to by numeral 8 is provided at the lower end of each of the runners 6, and these are capable of longitudinal adjustment on the runners to permit extension of the runners to meet the demands of uneven surfaces upon which the ladder must be supported.

Each of the extensible leg structures 8 consists of an elongated leg member 9 having a substantially square guide frame 10 secured to

a midpoint thereof and having a portion thereof of embracing the lowermost portion of the runner 6. This guide preferably has a roller 11 therein for riding the inside of the said corresponding runner 6.

It is also preferable that each leg member 9 have two pressure units and each of these units consist of a rectangular-shaped guide frame 12 having a roller 13 therein for riding the inside 10 of the corresponding runner 6 and a boss 14 at one end formed with a threaded opening for feedably receiving a screw 15. As can be seen in Figure 4, each elongated leg 9 extends through two guide frames 12, 12 and one guide frame 10, and these frames are secured to the leg member by screws or the like 16.

For each of the pressure units, a pressure foot 17 is provided and has a hollow neck 18 extending therefrom and into the hollow neck 18 extends the reduced and smooth end portion 19 of the corresponding pressure screw 15, which screw at its outer end has a handle 20.

A pin 21 is disposed through the neck 18 and passes through a circumferential groove 22 in the smooth portion 19 of the screw 15 and thus the screw 15 is swivelly connected to the pressure foot 17.

Obviously, by unloosening the screws 15, the legs 9 can be adjusted to the extent desired, 30 after which by feeding the screws inwardly, the pressure plate 17 will serve to firmly clamp the leg in place, by urging the rollers 13 against the inner side of the corresponding runner, while the pressure feet 17 bind against the outer sides 35 of the corresponding runner 6.

While the foregoing specification sets forth the invention in specific terms, it is to be understood that numerous changes in the shape, size, and materials may be resorted to without departing from the spirit and scope of the invention as claimed hereinafter.

Having described the invention, what is claimed as new is:

In combination with a ladder embodying a 45 pair of spaced runners rigidly connected by rungs, an adjustable extension leg on the lower portion of at least one of said runners, said extension leg embodying an elongated leg member disposed at the outer side of and parallel 50 with said runner, three rectangular guide frames embracing said runner and the leg member and each having a transverse roller journaled therein and contacting the inner side of the runner, means securing said guide frames to the leg member, two of said guide frames being posi-

tioned and spaced so as to engage respective ones of the two lowermost rungs of the ladder when the leg member is fully extended below the runner and to engage the next higher rungs when said leg member is fully retracted with its lower end substantially even with the lower end of said runner, and clamping screws threaded through the outer sides of said two guide frames and freely extending through the leg member to

bind against the outer side of said runner when adjusted inwardly, the remaining third guide frame being disposed to occupy a position just above the lower end of the runner when said leg member is fully extended and to engage the lowermost run of the ladder when said leg member is fully retracted.

NICHOLAS BENGERT.
